PRODUCTION OF TRI- AND PER-
CHLOROETHYLENES

Alfred A. D'Addieco, Wilmington, Del., and Harry O. Burrus, Lewiston, and Leslie J. Todd, Grand Island, N.Y., assignors to E. I. du Pont de Nemours and Company, Wilmington, Del., a corporation of Delaware

8 Claims. (Cl. 269—654)

This invention relates to an improved process for the production of chlorinated ethylenes by heating chlorethanes alone or in the presence of chlorine. It is particularly related to an improved process for the preparation of trichlorethylene and perchlorethylene from tetra-chlorethane.

Processes for the production of trichlorethylene and/or perchlorethylene by the pyrolysis of tetrachlorethane alone or in admixture with chlorine always yield high boiling chlorinated by-products. These high boiling materials represent a loss of process raw materials and constitute a difficult disposal problem since they have a toxic nature and tend to evolve corrosive vapors. Since trichlorethylene and perchlorethylene are manufactured in large commercial quantities even a small percent of these high boiling by-products represents a large quantity of undesirable waste.

One of the objects of this invention is to provide an improved process for the manufacture of chloroethylenes in which a major proportion of the high boiling by-products are converted to useful chloroethylenes. Another object is to provide a process for the production of trichlorethylene and perchlorethylene from chloroethanes alone or in admixture with chlorine in which the high boiling chlorinated by-products are converted to chloroethylenes. Further objects will become apparent from the following description.

The above enumerated and further objects of this invention are obtained principally in the production of trichlorethylene and perchlorethylene by the gas-phase pyrolysis of a partially chlorinated ethane raw material, containing at least 50% by weight of tetrachlorethane, alone or in the presence of chlorine, in which hexachlorethane obtained by the chlorination of the high boiling by-products of the pyrolysis are combined with the chloroethane raw material. This process involves a combination of the following steps:

(1) The chloroethane raw material or process feed mixture is adjusted to contain from at least 1%, or preferably 5%, by weight of hexachlorethane to an amount equivalent to less than one mole of hexachloroethane or one mole of hexachlorethane plus chlorine, if chlorine is combined therewith, for each mole of tetrachlorethane in the feed mixture.

(2) A high boiling by-product of the pyrolysis process is isolated by distilling the crude product thereof so as to obtain a fraction boiling in the range of from about 165° C. to about 250° C.

(3) The high boiling by-product fraction of step (2) is converted to hexachlorethane by reaction with chlorine at an elevated temperature and pressure.

(4) The hexachlorethane obtained in step (3) is combined with tetrachlorethane and other chloroethanes, such as pentachlorethane, recovered from the pyrolysis process, to produce the chloroethane process feed mixture of step (1).

A preferred alternate or modification of this process involves the addition of trichlorethylene to the chloroethane process feed mixture in amounts equivalent to up to two moles, or preferably 0.5 to 2 moles, for each mole of hexachlorethane in this mixture. When this is

done the conversion of hexachlorethane to chloroethylene products is appreciably increased. The addition of trichlorethylene is almost essential when the chloroethane feed is pyrolyzed in combination with chlorine since chlorine tends to lower hexachlorethane conversion to an impractical value.

The process of this invention is especially useful when it is employed in conjunction with the chloroethylene process of Copelin et al., U.S. Patent 2,957,923 (October 25, 1960). Although the Copelin et al. process gives a relatively low yield of high boiling by-product residue, the process of this invention for converting these products to useful chloroethylenes adds appreciably to the manufacturing economy.

In carrying out the process of this invention, the high-boiling by-product residue from the chloroethylene process is isolated following distillation of trichlorethylene, perchlorethylene, and chloroethanes, such as the unreacted tetrachlorethane and most of the pentachlorethane contained therein. This residue is then subjected to distillation to obtain a high-boiling fraction preferably, one which distills in the range of about 165° to about 240° C., at atmospheric pressure. The high-boiling by-product fraction is then subjected to liquid-phase chlorination preferably at temperatures of about 200° to 300° C. and pressures of about 200 to 300 pounds per square inch gauge (p.s.i.g.). Under these conditions it has been found that the high boiling by-product fraction is converted to hexachlorethane in a yield of approximately 90% or better. The hexachlorethane from the chlorination step is then added to the feed of the chloroethane pyrolysis process which thus comprises tetrachlorethane, pentachlorethane and hexachlorethane alone or in combination with chlorine gas in an amount equivalent to not over a total of one mole per mole of tetrachlorethane. As disclosed in the above-mentioned Copelin et al. patent, the chloroethane pyrolysis step is carried out at a temperature in the range 350° to 525° C. The molar ratio of hexachlorethane plus chlorine, if present, to tetrachlorethane in the feed mixture is less than one. In general, the molar ratio of hexachlorethane to tetrachlorethane in the chloroethane feed is about 0.05 to 0.4. When trichlorethylene is added to the pyrolysis feed gases, up to 0.5 to two molecular proportions are usually added per mole of hexachlorethane. In general, the trichlorethylene constitutes not over 5 to 10% by weight of the total feed gas. Under the conditions of this invention it has been found that the percent of high boiling by-products in the crude product does not increase when the pyrolysis is run in a continuous manner and all of the hexachlorethane obtained from the high boiling fraction is recycled.

The composition and amount of the high boiling by-products obtained in the chloroethane pyrolysis is determined both by the pyrolysis temperature and the composition of the feed with respect to the agents other than tetrachlorethane, e.g., pentachlorethane, hexachlorethane and chlorine. The exact composition of the high boilers is not known although the presence of such constituents as pentachlorobutadiene, hexachlorobutadiene, pentachlorobutene and hexachlorobutane have been demonstrated. The yield of hexachlorethane obtainable from high boilers by chlorination varies. However, with the combination of steps of this invention when carried out in the preferred manner, the yield of hexachlorethane as previously noted is 90% or better and may even be substantially quantitative. The yield of high boiling by-products other than unconverted hexachlorethane increases with the pyrolysis temperature so that for best results, the process should be carried out under conditions which make it possible to operate with practical

yields at the lowest possible pyrolysis temperature. When the process of this invention is employed in conjunction with the chloroethylene process of Copelin et al., U.S. Patent 2,957,923, the pyrolysis reactor comprises a heated zone and an unheated zone whose relative sizes are such that the exposure of the reaction products to the unheated zone is preferably about ten times that of the heated zone. In this connection, the yield of high boilers other than hexachlorethane per 100 pounds of trichloreethylene plus perchloreethylene has been measured as a function of the temperature of the unheated zone when the heated zone is about 450° C. These values are shown in Table 1.

Average temperature of heated zone (degrees C.):	High boilers excluding hexachlorethane (lbs./100 lbs. tri- + perchloreethylene)
325	0.7
350	1.0
375	1.4
400	1.9
425	2.4
450	3.1

The average temperature of the secondary unheated reactor zone is determined by the degree of insulation and the relation of wall area to volume.

The invention may be understood in more detail from the following illustrative examples. It should be understood that these examples should not be construed as limiting the invention.

Example 1

In a continuous gas-phase pyrolysis of tetrachlorethane, a feed gas mixture of tetrachlorethane, hexachlorethane obtained by the chlorination of high boiling by-products of the pyrolysis reaction, and a small amount of recycled pentachlorethane was passed through a reactor comprising a heated zone and an unheated zone at the rate of approximately 700 parts by weight per hour. The heated zone was maintained at a temperature of 448° C. and the unheated zone had a temperature of 438° C. The relative size of two reaction zones was such that exposure time in the unheated zone was about ten times that in the heated zone. The composition of the chlorehane feed mixture and the crude gaseous product in parts per 100 by weight are shown in the following table.

TABLE 2

Components	Chlorehane Feed	Products
Tetrachlorethane	87	2
Pentachlorethane	3	2
Hexachlorethane	10	1
Trichloreethylene		65
Perchloreethylene		12
High Boilers		2
Hydrogen Chloride		18
	100	100

The results of this example demonstrate that 90% of the hexachlorethane is consumed in the reaction and that the weight of high boiling by-products including unreacted hexachlorethane is relatively low. The net yield of useful chlorehane products is high since the pentachlorethane in the product can be recycled and at least 90% of the high boilers can be converted to hexachlorethane for recycle.

Example 2

The influence of trichloreethylene on the conversion of added hexachlorethane in the chlorehane pyrolysis process was demonstrated by two experiments substantially similar to Example 1 except that the unheated reactor zone was at a temperature of about 375° C. In one experiment 8 percent trichloreethylene was added in

the feed gas; in the other trichloreethylene was absent. At the temperatures employed in these experiments, the conversion was lower than in Example 1 but the yield of high boiling by-products was considerably reduced. The composition of the feed gas and gaseous product when trichloreethylene was added to the feed are shown in Table 2. These values are in parts per 100 by weight.

TABLE 3

Compounds	Chlorehane Feed	Product
Tetrachlorethane	80	12
Pentachlorethane	2	3
Hexachlorethane	10	3
Trichloreethylene	8	57
Perchloreethylene		9
High boilers		1
Hydrogen chloride		15
	100	100

As will be noted, the conversion of hexachlorethane was 70% in the presence of 8% trichloreethylene in the feed gas. In the experiment carried out in the absence of trichloreethylene, the hexachlorethane conversion was only 33%. In comparable experiments in which a 400° C. unheated reaction zone followed an approximately 450° C. heated zone, the hexachlorethane consumption was 45% in the absence of trichloreethylene and 84% when approximately 10% trichloreethylene was present in the feed gases.

Example 3

To determine the effect of chlorine on the conversion of hexachlorethane to chlorehane products in the tetrachlorethane pyrolysis reaction, a series of tests were carried out similar to Example 1 but with varying percentages of chlorine in the feed gas. In all of these tests the heated reactor zone was kept at about 450° C. and the unheated zone was about 400° C. Table 4 shows the variation of hexachlorethane conversion with variation of the weight percent of chlorine in the feed gases.

TABLE 4

Chlorine in feed gas:	Hexachlorethane converted
0.0	81
5.6	51
8.8	39
12.9	19

Example 4

The influence of trichloreethylene on the conversion of added hexachlorethane in the tetrachlorethane pyrolysis reaction when chlorine is present is illustrated by two tests substantially similar to Example 1 in which the heated reactor zone was at 455° C. and the unheated zone was at 377° C. In both of these tests the feed gas contained 7% by weight of chlorine. However, in the first test, 4A, only 1% trichloreethylene was present in the feed gases whereas 7% was present in the second test, 4B. The composition of feed gas including chlorine and product in parts per 100 by weight is shown for both of these tests in Table 4.

TABLE 5

Components	Test 4A		Test 4B	
	Feed Gas	Product	Feed Gas	Product
Chlorine	7		7	
Tetrachlorethane	79	2	75	7
Pentachlorethane	3	9	9	5
Hexachlorethane	10	9	9	5
Trichloreethylene	1	49	7	50
Perchloreethylene		12		17
High boilers		1		1
Hydrogen chloride		20		20
	100	100	100	100

In Test 4A, the hexachlorethane conversion is only 10% whereas in Test 4B in which the feed gas contains 7% trichlorethylene, the hexachlorethane conversion is 44%.

The embodiments of the invention in which an exclusive property or privilege is claimed are as follows:

1. In a process for the production of trichlorethylene and perchlorethylene by the gas-phase pyrolysis of a chloroethane feed mixture containing at least 50% by weight of tetrachlorethane at a temperature in the range of 350°-525° C. the improvement comprising, in combination, the steps:

- (a) employing in the gas-phase pyrolysis step a chloroethane feed mixture containing at least 1% by weight of hexachlorethane in which the mole ratio of hexachlorethane to tetrachlorethane is less than one,
- (b) separating a high boiling by-product by distilling the crude chloroethylene product of said pyrolysis to obtain a fraction boiling in the range of about 165° to about 250° C.,
- (c) reacting the said by-product fraction with chlorine in the liquid phase at an elevated temperature of about 200° to about 300° C. and a pressure of about 200 to about 300 p.s.i.g. to produce hexachlorethane, and
- (d) combining hexachlorethane obtained in the by-product chlorination of step (c) with tetrachloroethane to obtain the chloorethane feed mixture of step (a).

2. The process of claim 1 wherein up to two moles of trichlorethylene are added to the chloorethane feed mixture for each mole of hexachlorethane.

3. In a process for the production of trichlorethylene and perchlorethylene by the gas-phase pyrolysis of a chloorethane feed mixture containing at least 50% by weight of tetrachlorethane at a temperature in the range of 350°-525° C. the improvement comprising, in combination, the steps:

- (a) employing in the gas-phase pyrolysis step a chloroethane feed mixture containing at least 1% by weight of hexachlorethane in combination with chlorine in such proportion that the mole ratio of hexachloroethane plus chlorine to tetrachlorethane is less than one,
- (b) separating a high boiling by-product by distilling the crude chloroethylene product of said pyrolysis to obtain a fraction boiling in the range of about 165° to about 250° C.,
- (c) reacting the said by-product fraction with chlorine in the liquid phase at an elevated temperature of about 200° to about 300° C. and a pressure of about 200 to about 300 p.s.i.g. to produce hexachlorethane, and
- (d) combining hexachlorethane obtained in the by-product chlorination of step (c) with tetrachloroethane to obtain the chloorethane feed mixture-chlorine combination of step (a).

4. The process of claim 3 wherein up to two moles of trichlorethylene are added to the chloorethane feed mixture for each mole of hexachlorethane.

5. In a process for the production of trichlorethylene and perchlorethylene by the gas-phase pyrolysis of a

chloorethane feed mixture containing at least 50% by weight of tetrachlorethane at a temperature in the range of 350°-525° C. the improvement comprising, in combination, the steps:

- 5 (a) employing in the gas-phase pyrolysis step a chloroethane feed mixture containing at least about 5% by weight of hexachlorethane in which the mole ratio of hexachlorethane to tetrachlorethane is less than 0.4,
- (b) separating a high boiling by-product by distilling the crude chloroethylene product of said pyrolysis to obtain a fraction boiling in the range of about 165° to about 250° C.,
- (c) reacting the said by-product fraction with chlorine at a temperature of about 200° to about 300° C. and about 200 to about 300 pounds p.s.i.g. to produce hexachlorethane, and
- (d) combining hexachlorethane obtained in the by-product chlorination step (c) with tetrachlorethane to obtain the chloorethane feed mixture of step (a).
- 6. The process of claim 5 wherein 0.5 to two moles of trichlorethylene are added to the chloorethane feed for each mole of hexachlorethane.
- 7. In a process for the production of trichlorethylene and perchlorethylene by the gas-phase pyrolysis of a chloorethane feed mixture containing at least 50% by weight of tetrachlorethane at a temperature in the range of 350°-525° C. the improvement comprising, in combination, the steps:
- (a) employing in the gas-phase pyrolysis step a chloroethane feed mixture containing at least 5% by weight of hexachlorethane in combination with chlorine in such proportion that the mole ratio of hexachloroethane plus chlorine to tetrachlorethane is less than one,
- (b) separating a high boiling by-product by distilling the crude chloroethylene product of said pyrolysis to obtain a fraction boiling in the range from about 165° to about 250° C.,
- (c) reacting the said by-product fraction with chlorine at a temperature of about 200° to about 300° C. and about 200 to about 300 p.s.i.g. to produce hexachlorethane, and
- (d) combining hexachlorethane obtained in the by-product chlorination of step (c) with tetrachloroethane to obtain the chloorethane feed mixture-chlorine combination of step (a).
- 8. The process of claim 7 wherein 0.5 to two moles of trichlorethylene are added to the chloorethane feed for each mole of hexachlorethane.
